UNITED STATES PATENT OFFICE.

WILLIAM W. DODGE, OF WASHINGTON, DISTRICT OF COLUMBIA.

JAR-CLOSURE.

1,401,467.

Specification of Letters Patent. Patented Dec. 27, 1921.

Application filed February 17, 1919. Serial No. 277,465.

To all whom it may concern:

Be it known that I, WILLIAM W. DODGE, a citizen of the United States, residing at Washington, in the District of Columbia, have invented certain new and useful Improvements in Jar-Closures, of which the following is a specification.

This invention pertains to closures or stoppers for milk jars or bottles, and like containers, and consists in a flat disk of pulp board or other suitable material, of a size to fit the seat in the neck or mouth of the container, and having formed therein by facewise compression a seat or depression 15 in its upper or outer face; and a lifter lying in such depression and flush with or below the top face of the disk, said lifter being made fast to the disk in any convenient way.

20 The invention is illustrated in several slightly variant forms in the accompanying drawings, in which:

Figure 1 is a top plan view of a closure embodying my invention in its preferred 25 form, that is to say, with a lifter formed of wire;

Fig. 2, a bottom face view of the same.

Fig. 3, a section on the line 3—3 of Fig. 1, showing the lifter in the position which 30 it occupies when the disk is applied to close or seal the mouth of a container and indicating by dotted lines the position to which it is raised for use;

Fig. 4, a perspective view of another embodiment of the invention wherein the lifter is formed of thin sheet metal;

Fig. 5, a sectional view on the line 5—5 of Fig. 4;

Fig. 6, a sectional view on the line 6—6 of 40 Fig. 4;

Fig. 7, a perspective view of the lifter shown in Figs. 4, 5 and 6, but cut away to lighten the bail or handle portion of the lifter;

45 Figs. 8 and 9, perspective views of a disk or closure having a seat or depression in the upper face formed by compression of the body of the disk and without cutting, removing or detaching any portion of the disk;

50 Figs. 10 and 11, perspective views of the disks shown in Figs. 8 and 9, provided with a lifter or tab of flexible material such as tough paper, woven fabric, or the like, suitably attached near one end to the disk;

55 Figs. 12 and 13, perspective views of the

closure of Figs. 10 and 11 with the tab or lifter raised at its free end;

Fig. 14, a section on the line 14—14 of 60 Figs. 10 and 11;

Fig. 15, a face view of a closure showing the tab or lifter seated in a depression formed in the middle portion of the disk and attached to the disk at its midlength;

Fig. 16, a sectional view through the 65 mouth of a bottle, jar or container showing my improved stopper or closure in position.

Better to explain the nature and purpose 70 of the invention, a brief statement of the prior art will be useful.

Heretofore, stoppers or closures of this general type, for bottles and other containers, have been made in the form of a simple disk of pulp board of suitable thickness, paraffined on one or both faces, and 75 pressed to a seat within the mouth of the container. While such simple disk formed a very satisfactory seal or closure, it was found necessary to employ a special tool or implement for its removal, usually a sharp 80 implement of some sort, which punctured the disk and served as a lifter. This was found objectionable in that the disk was destroyed or impaired for further use, as where a portion only of the contents of the 85 container were removed and it was desirable to reseal the bottle.

To meet this difficulty the disks were provided with a tab or ear projecting outward from the circumference of the disk proper, 90 but this construction involved a considerable waste of material in cutting the disks, and required a specially designed container mouth for its convenient and efficient application and use.

95 Another type of lifter or handle consists of a tab of paper, pulp board, or the like, stapled or otherwise secured to and lying upon the face of the pulp board disk. While this is found to be a very efficient device so far as concerns sealing the container and affording ready means of removal of the stopper, projection of the tab above the surface of the disk is objectionable because it prevents the ready and even stacking of 100 the disks or stoppers in tubes for shipment, or use in magazines from which to feed them to bottles or containers in bottling establishments.

105 To overcome the last-noted objection, two plans have been resorted to. Under the first a substantially U-shaped cut is made

in the face of the disk, outlining a tab or handle, the cut being of a depth equal to one-half the thickness of the pulp board of the disk, and a staple is then applied at the base 5 or uncut end of the tab thus outlined, which tab is thereafter separated or split off from the body of the disk, but is prevented by the staple from being torn completely off in thus splitting the tab from the body of the disk, 10 or when using it as a handle or lifter.

This construction avoids the unequal thickness of the disk or projection of the tab above the face of the disk, but produces a tab of inadequate strength at best, and one 15 which speedily becomes further weakened by moisture reaching the relatively porous and absorbent interior of the disk and under surface of the tab, by reason of the hard finished and paraffined surface of the pulp 20 board being cut or broken, and the porous interior being exposed by the splitting off or separation of the tab from the body of the disk. This frequently results in a small quantity of milk or other liquid getting 25 upon the face of the disk and under the tab, the latter because of moisture condensing upon the stopper when the container is placed in an ice-chest, or left exposed to the weather, as frequently happens between 30 livery of the containers and arrival of servants or domestics to take them indoors.

Under the second plan last referred to, a similar cut is made in the face of the disk of about one-half its depth or thickness, and 35 the portion so cut or outlined is completely removed from the disk, leaving a seat or depression in which is placed and secured by a staple or like fastener, a tab of pulp board, paper, or the like. This plan, while 40 permitting the use of a stronger tab or lifter, involves the use of special machinery for its manufacture, exposes the relatively porous and absorbent interior of the disk to moisture, and so weakens the disk in the 45 cutaway portion that the fastening staple of the tab or lifter is liable, at least occasionally, to pull through or tear out of the disk when it is sought to use it for removal of the disk or stopper from the mouth of the 50 container.

Lifters of wire and of sheet metal have also been proposed, but these have in every instance been made to lie upon and project above the surface of the disk, interfering 55 with proper stacking and feeding.

To remedy the difficulties noted, I form the necessary seat or depression in the face of the disk by compression, without cutting or removing any portion of the disk, and 60 in this way I produce a stopper or closure which presents no projection or proturbation of any sort on either its upper or its lower face. Such stoppers or disks may be stacked evenly and with their faces parallel, and 65 can be readily slid one relatively to another

without liability of locking together or engaging one another, whether in stacking preparatory to packaging and shipping, or in being delivered from a magazine or holder to the mouths of containers in bottling 70 establishments.

Referring again to the drawings and first to Figs. 1 to 3 inclusive, A indicates a flat disk, which may be of any usual or suitable material, and is commonly of circular form, 75 though the shape may be varied at will. B indicates a lifter, shown in said figures in the form of a light wire staple or bail, the free ends *a* of which are passed through the disk from its upper surface and bent back 80 parallel with the under surface, preferably at an angle of about 45° to the sides or limbs of the body of the staple, but directed inward from the circumference or in the general direction of the body of the staple 85 instead of in the opposite direction. The body of the staple is, before completion of the stopper, laid parallel to and flush with the face thereof, occupying in the finished disk a seat or depression C formed in the 90 face of said disk. This seat or depression may, in the case of the wire lifter, best be formed by applying pressure from the upper and lower sides of the disk, sufficient to embed said lifter, both its body and its back- 95 wardly turned ends, in the disk. If preferred, however, such seat or seats may be produced through a separate operation prior to application of the lifter. The ends may be turned toward or away from each other. 100

The reasons for giving to the ends of the lifter the direction or position shown and above referred to are that it is necessary that said ends turn backward in the general direction of the main body of the staple in order 105 that the body and end portions may mutually serve to hold each other to their seats in the faces of the disk, and the deflection of the ends out of line with the body portion is to prevent cutting entirely or practically 110 through the disk from face to face, as would happen were the backwardly turned ends alined with the body portion of the lifter.

To facilitate the lifting of the handle or lifter from its seat, a slight depression D 115 may be made just in front of the free end of the lifter, as indicated in Figs. 1 and 3, and this may advantageously be done with the several variant forms or embodiments 120 of my invention.

In Figs. 4 to 7 inclusive, I have shown the lifter as formed of light sheet metal. In these figures A' indicates the disk of pulp board or like material; B' the lifter or handle of sheet metal; C' the lifter seat or 125 depression; and D' the extension thereof or supplemental depression facilitating the raising of the lifter from its seat. This depression as in the previous form, permits the ready engagement of the lifter by the 130

finger-nail, and renders unnecessary any special implement.

The lifter or handle B' is preferably made in the form of a substantially rectangular plate, as shown in Figs. 4 and 5, which may, however, be cut out to skeleton form as shown in Fig. 7. One end of this lifter B' is provided with one or more prongs or spurs a' , which are turned down-
ward at substantially a right angle to the body of the lifter, and are pressed or driven through the disk A' from its upper to its lower surface and bent over or clenched, as indicated in Figs. 5 and 6. It is preferred to provide three prongs or spurs, one at the end and two projecting laterally from opposite sides, as this gives a more secure fastening, and causes the lifter to bend readily at a point near the side prongs.
In practice I find it expedient to form the seat or depression C' by applying to the lifter sufficient pressure to embed it and its prongs in the disk, so that each shall lie flush with the face of the disk on which it appears, but if desired the seats or depressions may be made before application to the lifter.

If desired the lifter, both in the wire and in the sheet metal structure, may have formed in it a slight depression or bend close to its point of attachment to the disk, to facilitate and locate the final bending preparatory to use as a lifter. This is indicated at c in Figs. 1, 3, 4, 5 and 7. It is not, however, essential, particularly if light wire or sheet metal be used, or if the lifter be of the skeleton form illustrated in Fig. 7.

In Figs. 8 to 16 inclusive I have illustrated a third embodiment. In this a disk A^2 has a seat or depression C^2 formed in its upper face by compression, and extending from the central portion of the disk toward and preferably to or nearly to the circumference. This depression I produce by pressing or forcing a suitable die against the face of the disk, and compressing its body throughout the bearing area of the die to about one-half its normal thickness. This mode of producing the seat or depression preserves the hard finished surface of the disk, and in fact by making more dense the pulp board throughout such area, tends to make the same stronger and tougher than in its original condition, at the same time preventing absorption of moisture by or entrance thereof into the body of the disk. Within this seat or depression C^2 I place a flat tab, lifter or handle B^2 , which may be made of strong or tough paper, such as parchment paper or bond paper, or of pulp board, woven fabric, or the like, buckram being found a very serviceable material for the purpose. The tab or lifter should be sufficiently thin to prevent its projecting above the surface of the disk. It may con-

veniently be made fast to the disk by a staple b , located at any point between the extremities of the tab. Fig. 15 shows it at the midlength so that either or both ends of the tab may be raised and used as a handle or lifter.

It is possible to seat the tab C^2 flush with the face of the disk A^2 by direct pressure sufficient to force the tab into or embed it in the disk, but I deem it preferable, particularly if the tab be made of pulp board or other relatively thick material, to produce the seat initially and by a separate operation, though the present application pertains to the finished article rather than to the mode of manufacture or production.

In the practical manufacture of stoppers of this general type it is customary to apply paraffin to the opposite faces of the disk as the final operation, the otherwise completed disk being passed between rollers bearing a thin film of melted paraffin. This operation fills with paraffin any slight spaces in the seat or depression not occupied by the lifter, in whatever one of the forms here shown, and tends to hold such lifter more securely in its seat, thus preventing liability or tendency of the same to spring or curl upward and project above the face of the disk. It also insures the coating of the metal with paraffin, thus effectually guarding against corrosion of such metal, whether of the lifter or of the securing staple, and precluding any possible injury to the contents of the container by reason of the presence of the small metal points showing on the under side of the closure. The coating is indicated at d , Figs. 3 and 6, but is omitted in the other figures in the interest of clearness.

By the simple expedient above set forth I have produced a stopper or closure for containers, which at once avoids the objections or overcomes the defects of prior closures of this general type, yet affords every advantage offered by any of the prior forms, and which can be produced with fewer operations and at less expense than those now generally used.

It will of course be understood that slight variations may be made without departing from the spirit of my invention. For instance, the lifter when of metallic form, may be folded about or clasp the periphery of the disk instead of passing through the same. This and similar slight modifications I deem as the mere equivalent of passing through the disk, the prominent feature of the invention being the compression of the disk to form a seat in which the lifter may lie flush with the face or faces of said disk.

Having thus described my invention what I claim is:—

1. A stopper or closure for bottles and

like containers, comprising a disk compressed to form a seat or depression in its face; and a lifter seated in said depression wholly within the thickness of the 5 material of the disk, and made fast to the disk at a point between the extremities of the lifter.

2. In combination with a sealing disk or stopper having a portion of its face 10 compressed below the level of the surrounding surface to form a seat or depression, a metallic lifter seated in said depression wholly within the thickness of the material of the disk and having a portion extending 15 therethrough and clenched upon the under side thereof, and flush therewith.

3. In combination with a sealing disk or stopper having a seat in its face formed by facewise compression of a portion of 20 its area, a wire lifter lying within said seat or depression and wholly within the thickness of the material of the disk, and

having its extremities passed through the disk and clenched upon its rear side, the clenched ends extending in the general 25 direction of the body of the disk but at an angle thereto, and flush with the face of the disk.

4. A stopper or closure for bottles and like containers, comprising a disk having 30 a portion of its area compressed to form a seat or depression in its face; a lifter seated in said depression wholly within the thickness of the material of the disk and made fast to the disk; and a coating of paraffin 35 covering the face of the disk and the lifter, and serving both to render the disk waterproof and to aid in holding the lifter in the seat or depression and prevent its 40 springing therefrom.

In testimony whereof I have signed my name to this specification.

WILLIAM W. DODGE.
